United States Patent Office.

S. B. HEWETT, JR., OF EAGLE GROVE IOWA.

Letters Patent No. 75,759, dated March 24, 1868.

IMPROVEMENT IN WIRE-FENCE KEY.

The Schedule referred to in these Letters Patent and making part of the same.

TO ALL WHOM IT MAY CONCERN:

Be it known that I, S. B. HEWETT, Jr., of Eagle Grove, in the county of Wright, and State of Iowa, have invented a new and useful Improved Wire-Fence Key; and I do hereby declare that the following is a full, clear, and exact description of the same, reference being had to the accompanying drawings, and the letters and figures marked thereon, which form a part of this specification, and in which—

Figure 1 represents a top view of my improved key, and

Figure 2 a side elevation of the same, showing its application.

The nature of my invention consists in a novel device for tightening the wires of wire fence, or other wires or cords which it is desirable to make taut.

To enable those skilled in the art to manufacture and use my invention, I will proceed to describe the same with particularity.

The same letters of reference represent the corresponding parts in the different figures.

A. is a grooved wheel, the flanges of which are extended on opposite sides, so as to admit of holes B for the pins C. There is a vertical slot, D, in said wheel, which is made sufficiently wide to admit the wire or cord that is to be tightened; and there are two ledges or lips, E, cast upon or attached to the top of the wheel, said ledges or lips being so constructed and arranged as to admit of a wrench or lever being slipped under and between them, for the purpose of turning the wheel, as hereinafter described. The dotted line F shows the thickness of the wall or drum of the wheel. I ordinarily cast the whole device, except the pins C, in a single piece of iron, but it may be made of any suitable material.

The operation of my invention is as follows: I place the wheel upon the wire or cord H, by causing the said wire to pass into the slot D; then, by means of a wrench or lever held by the lips E, as above described, I turn the said wheel A, and thereby wind the wire on the drum of said wheel till it is made sufficiently tight, when, by placing the pins C in the holes B, as shown in fig. 2, it is kept from turning back, and the wire is held taut, as desired.

The principal use for my improved key is tightening the wires composing ordinary wire fences. In doing this, I place a key on each of the wires, and turn it, as above described, till the wire is sufficiently tight, when I put in two nails, or any suitable pins, to hold the key from turning back, and the key is allowed to remain suspended upon the wire. If the wire is found to be drawn too tight as cold weather comes on, it is simply necessary to remove the pins, and allow the key to turn till the wire is unwound sufficiently to give it the desired tension, when the pins are replaced, and the key hangs suspended as before.

Having thus fully described the construction and operation of my invention, I claim—

1. The combination of the wheel A, provided with flanges, as shown, and a slot, D, with the removable pins C, or their equivalent, arranged and operating as and for the purposes herein set forth.

2. In combination with the above, I claim the arrangement of the jaws or lips E, as and for the purposes specified.

S. B. HEWETT, JR.
